UNITED STATES PATENT OFFICE.

WILLIAM A. PALMER, OF LUDLOW, KENTUCKY.

CAR-COUPING.

984,390.

Specification of Letters Patent. Patented Feb. 14, 1911.

Application filed April 21, 1910. Serial No. 556,807.

To all whom it may concern:

Be it known that I, WILLIAM A. PALMER, a citizen of the United States, residing at Ludlow, in the county of Kenton and State 5 of Kentucky, have invented certain new and useful Improvements in Car-Couplers; and I do hereby declare the following to be a full, clear, and exact description of the invention, such as will enable others skilled 10 in the art to which it appertains to make and use the same.

This invention relates to improvements in car couplers which may be automatically coupled and locked and which may be automatically uncoupled upon the release of 15 the locking means, or the knuckles of which may be thrown open by operating the locking means and kicker manually.

One object of the invention is to provide 20 a coupler which is quick in the operation of coupling and uncoupling and which forms a positive and strong interlock for the coupling jaws. In order to accomplish this end I provide a particular form of locking block and kicker coöperating with the 25 beveled face on the tail of the knuckle, and also coöperating with elevations and depressions formed on the coupler to raise and lower the axis of locking block and kicker 30 during its rotary movement.

While the invention is not restricted to the exact details shown and described, still for the purpose of disclosure reference is had to the accompanying drawings showing 35 a practical embodiment of same, in which drawings like characters designate the same parts in the several views, and in which—

Figure 1 is a horizontal longitudinal section on the line 1—1 of Fig. 2, looking in the direction of the arrows. Fig. 2 is a cross section on the line 2—2 of Fig. 1, looking in the direction of the arrows. Fig. 3 is a vertical longitudinal section on the line 3—3 of 45 Fig. 1, looking in the direction of the arrows. Fig. 4 is a longitudinal vertical section on the line 4—4 of Fig. 1 and looking in the direction of the arrows, and Fig. 5 is a perspective view of the locking block and carrier.

1 designates a draw bar having the usual draw head jaws 2 and 3, the jaw 3 being shown provided with the usual longitudinal recesses 4 and curved face 5, and the jaw 2 having hinged thereto the coupling knuckle 6 by means of the hinge pin 7 passing through the knuckle and the upper and

lower apertured ears 8 and 9 extending from the jaw 2, the lower apertured ear 9 being disposed a slight distance above the bottom of the jaw to form a recess or shoulder 10, the cotter pin 11 passing through the hinge pin 7 and abutting against said shoulder 10 to prevent the hinge pin from turning and wearing.

The knuckle 6 is provided with a tail 65 piece having a toe 12 and a heel 13, the upper and lower faces of the toe being recessed and beveled to coöperate with the nose on the locking block and the kicker, hereinafter referred to. The heel 13 forms with the 70 tail member a recess 14 adapted to coöperate with an inwardly projecting lug 15 formed on the jaw 2.

Referring to Fig. 5, the combined locking block and kicker consists of a body portion 75 16 provided with a beveled nose member 17 comprising the locking block, and being also provided with a finger or kicker 18 at the rear of said body member and downwardly projecting in a position to one side of said 80 nose or locking block. The body portion is also provided with a horizontally disposed rear lug 19, and the combined arrangement is journaled within the draw head by means of the pintle 20 operating in a vertical elongated slot 21 cut in the jaw 3 of the draw head, and also by a lateral arm 22 journaled in a horizontal slot 23 cut in the opposite jaw 2. The arm 22, on its outer end, is provided with an apertured ear 24 to which 90 may be attached an operating link for rotating the combined locking block and kicker on the axis of the pintle 20 and the arm 22. The top and bottom of the inside surfaces of the draw head are recessed, as at 95 25, to permit of the oscillation of the locking block and kicker, the lower surface being provided with a slot 26 in line with the kicker finger 18, and adjacent this slot 26 is formed a shelf or ledge portion 27, the upper 100 surface of which is depressed, as at 28, forming a cam 29 adapted to be engaged by the lug 19 during oscillation of the locking block and kicker, the pintle 20 being elevated in the slot 21 so that the kicker is 105 given a slight side thrust as well as a forward motion during rotation, and engaging beneath the beveled recess surface of the tail member positively and rapidly opens the knuckle, the locking block 17 having in the 110 meantime been elevated from its position between the end face 12^a of the toe and the

inner flat face 3^a of the jaw 3. It will also be observed that the locking block is so disposed with relation to the kicker that, as soon as the lug 19 passes to either side of the 5 cam 29, the center of gravity of the combined member is shifted to one side or the other of the axis, and the combined locking block and kicker is more quickly forced into proper position. Also, as the lug 19 rides 10 over the cam surface 29, the pintle 20 being elevated in its slot, upon reaching the other side of the cam the combined member tends to drop downwardly by its weight, and the lug 19 sliding over the decline of 15 the cam surface tends to also more quickly thrust the parts into their proper positions. It will also be observed that by the arrangement of the offset heel 13 and the lug 15, when the locking block 17 is in the locking 20 position shown in Fig. 1 the tail member of the knuckle is held against transverse movement, and should the hinge pin break the heel 13 would engage against the lug 15 and still maintain the coupler closed.

25 Having thus described one form of the invention, the particular features of novelty are pointed out in the following claims:—

1. In a car coupler, the combination of a hollow draw head, a knuckle hinged thereto and provided with a tail member disposed within said hollow head, a combined locking block and kicker coöperating with said tail member, a pin and slot connection between said draw head and one side of said 30 combined locking block and kicker, permitting a limited vertical movement of one side of said locking block and kicker, means for oscillating said locking block and kicker, and means located on the coupler head and 35 engaged by said locking block and kicker for slightly elevating the same while being oscillated, substantially as described.

2. In a car coupler, the combination of a hollow draw head, a knuckle hinged thereto 45 provided with a tail member disposed within said draw head, a rotatably mounted locking block and kicker coöperating with said tail member, said locking block being normally disposed forwardly and said kicker

being normally disposed rearwardly of the 50 axis of said locking block and kicker, and said kicker being disposed to one side of said locking block, means for oscillating said locking block and kicker, and means for slightly elevating and lowering same during 55 oscillation comprising a raised cam surface disposed within said draw head, and a rearwardly projecting lug disposed at substantially right-angles to said kicker and adapted to engage said raised cam, substantially 60 as described.

3. As an element in a car coupler, the combined locking block and kicker comprising a body portion having a horizontal forwardly projecting locking block and a rear 65 downwardly projecting kicker offset from the plane of said locking block and also being provided with a rearwardly extending horizontal lug lying within the plane of said locking block, said lug being adapted to engage a cam surface located on the coupler head to move said element vertically during operation and said element being provided at one side with a pintle and at the other side with a shank, said pintle and 70 shank forming trunnions for said element, substantially as described.

4. In a car coupler, the combination of a hollow draw head having recesses on its upper and lower faces, a knuckle hinged thereto and having a tail member disposed within said hollow draw head, a cam disposed within said lower recess, a combined locking block and kicker operating within 80 said recesses and coöperating with said tail, said combined locking block and kicker having a rearwardly extending lug adapted to engage said cam, and said combined locking block and kicker having an axis journaled at one end in a vertical slot and at the other end in a horizontal slot formed in said draw head, substantially as described.

In testimony whereof, I affix my signature, in presence of two witnesses.

WILLIAM A. PALMER.
